JOHN D. LAWRENCE AND STANLEY W. NICHOLSON, OF TOLEDO, OHIO, ASSIGNEES, BY
MESNE ASSIGNMENTS, TO THE DURA COMPANY, OF TOLEDO, OHIO, A CORPORATION
OF OHIO

WINDOW REGULATOR

Application filed September 4, 1920. Serial No. 408,289.

This invention relates to vehicle window control mechanisms and more particularly to control mechanisms for automobile windows.

It is one of the objects of the invention to provide a control mechanism for a sliding window member comprising a combined actuating and locking device and a counterbalancing device, said devices being formed as dependent units, whereby the assembly of the parts and the installation of said devices in a motor vehicle is facilitated and certain frictional losses are avoided.

A further object of the invention is to provide a window controlling means, particularly applicable to a window employing a vertical sliding window member, one edge of which is at least in part inclined to the vertical, so that in certain positions of sliding adjustment the inclined edge portion is withdrawn from its slideway. The present invention applied to such a window functions to maintain the window member pressed into firm engagement with its vertical slideway when the inclined edge portion of said window is free.

The invention consists in the structural features and arrangements of parts herein-after fully described and illustrated in the accompanying drawings, wherein:

Figure 1 is an exterior side elevation of the forward portion of a closed vehicle body showing a window of a type to which the invention has a special application;

Figure 2 is an interior view of the door in which said window is arranged showing the application to said window of the control mechanism;

Figure 3 is a fragmentary enlarged portion of Figure 2, showing in particular a bumper or stop member which limits movement of the actuating means;

Figure 4 is an end view of the same;

Figure 5 is an enlarged detail view of the actuating unit showing the locking means;

Figure 6 is a section on line 6—6 of Figure 5;

Figure 7 is an enlarged cross section taken through the door in which the control window is provided, the plan of section being above the controlling mechanism;

Figure 8 is an enlarged inner side view of the control handle removed from the partition with which it is associated.

In these views the reference character 1 designates a vehicle body of the closed type, the front 2 of which body inclines to some extent rearwardly from the vertical as it extends upwardly from the level of the hood. The forward door 3 of the body 1 has a window opening 4 in its upper portion and a closure for said opening is formed by a vertically slidable glass plate 5, which when lowered is adapted to enter a chamber 6 formed in the lower portion of said door. The portion 7 of the door, which is adjacent the inclined front 2 of the body 1 is inclined to conform to the front 2 so that the forward margin of the window opening 4 is non-vertical. Consequently the edge 8 of the glass 5, which in the closed position of the window engages the member 7, is similarly inclined. Therefore, when the window is lowered to any appreciable extent, the edge 8 is withdrawn from engagement with the portion 7 of the door. Under these conditions, in order to adequately support the glass 5, it is desirable to maintain the vertical edge thereof pressed firmly against the vertical edge of the window opening. This result is accomplished by the actuating and counterbalancing means which will now be described.

9 is a control arm which is disposed within the chamber 6 of the door and is pivoted at one end upon a bracket member 10, while its other end is provided with a head or roller 11 engaging beneath the glass 5. Said arm is adapted to be rotatively actuated by a handle member 12 engaging the pivotal end of said arm and located adjacent the inner face of the door. Preferably engagement of the arm 9 with the glass 5 is effected by arranging the head 11 within a laterally opening channel portion 13 of a sheet metal strip extending transversely of the glass 5, and having an upwardly opening channel portion 14, embracing and secured to the lower edge portion of the glass. By rotation of the handle 12, the control arm 9 may be shifted to any position intermediate its upper and lower limits, the former which is shown in

full lines in Figure 2, while the latter is indicated in dash lines in said figure, and through such movement of said arm the glass is raised or lowered to any desired position. 5 Both of the limiting positions of the arm 9 are established by engagement of the head 11 with a bumper 14^a, formed preferably of rubber and so disposed within the channel member 13 as to be engaged by the head 11 when the arm 9 projects vertically upward 10 or downward.

The invention further provides a counterbalancing means consisting of an arm 15 disposed within the chamber 6 and provided 15 at one end with a roller 17 bearing upwardly upon the channel member 13, the other end of said arm being pivoted upon a bracket 16 secured to the opposite edge member of the door from that which carries the actuating 20 mechanism. An upward effort such as will properly counterbalance the weight of the sliding glass 5 is exerted upon the arm 15 by coiled springs 18 attached to said arm adjacent its pivot and extending upwardly to 25 a suitable anchorage point within the chamber 6.

To prevent any shifting of the sliding window member from its desired position of adjustment owing to vibration of the vehicle, 30 it is desirable to provide a locking means whereby the control arm 9 will be held fixed in any of its positions of adjustment. So far as concerns the present improvement, this locking means may be of any type, as 35 for example that which is illustrated in Figures 5 to 8 inclusive, and which will now be described.

19 designates the pivot, or trunnion member of the arm 9 which member is journaled in the bracket 10. Said trunnion member is provided with two parallel sockets 20, extending transversely of said arm and arranged one at each side of the pivotal axis, each socket terminating at one end short of the adjacent side of the trunnion, as is shown 45 in Figures 5 and 6. In each of the sockets 20, there is mounted a sliding dog 21 provided at its outer end with a tooth 22 adapted to project into a registering one of a series 50 of notches 23, formed interiorly of the bracket 10. A coiled compression spring 24 is disposed in the inner portion of each socket and has one end bearing against the associated dog 21, to urge the latter outwardly 55 and force the tooth 22 of said dog into a registering notch 23. Each tooth 22 is beveled at one side thereof to permit a turning of the trunnion 19 in one direction relative to the bracket 10 without withdrawing the dog 60 from notch engaging position. The beveled sides of the teeth 22 are reversely positioned however, with respect to the turning movement of the trunnion 19, so that one tooth 65 normally restrains the trunnion from turning in one direction and the other resists

turning in the opposite direction. In the present instance the teeth 22 have their inner or adjacent sides beveled.

The swinging movements of the arm 9 and the releasing movements of the dogs 21 upon engagement with notches 23 are actuated by the handle member 12 mounted to turn freely upon a pivot stud 25 projecting axially from the trunnion 19. The handle member 12 is retained in loose pivotal engagement with said stud by screw 26, or in any other suitable manner.

The handle 12 is provided upon one side of its inner end portion with a segmental boss or projection 27, which extends through a registering segmental slot 28 in the adjacent end of the trunnion part 19. When the handle has been rocked a sufficient distance to place either end of its boss 27 in contact with the corresponding end wall of the slot 28, a continued rocking movement of the handle will impart a rocking movement in the same direction to the trunnion part 19 and arm 9. A pin 29 projects outwardly from each dog 21 into the respective end portion of the slot 28 and in the path of movement of the respective end of the boss 27 whereby said boss when rocked in either direction, will act against the pin 29 toward which it is rocked, so as to effect a sufficient movement of such pin and of the attached dog to withdraw the tooth 22 of said dog from notch engaging position prior to engagement of said boss with the end wall of slot 28 which it is approaching. When the pin 29 has moved from normal position, it enters a registering notch 30 in the respective end wall of the slot 28. It is thus evident that a movement of the handle 12 to effect swinging of the arm 9 in either direction first effects release of the pawl 21 so as to permit the desired swinging of said arm and then positively actuates the desired swinging, the other dog 21 meanwhile riding freely over the notched interior face of the bracket 10. The handle when released, moves to neutral position under tension of the springs 24 acting against the dogs 21, and thus permits both dogs to have locking engagement with the bracket member and to thereby hold the arm 9 in the desired adjustment.

It is to be noted that the counterbalancing arm 15 engages the sliding window member in proximity to the edge portion of the latter, which is inclined to the vertical, while the actuating arm in all positions of adjustment of the mechanism engages the window member at a point more remote from the inclined edge thereof than does the counterbalancing arm. This relation between the points of engagement of the two arms and the window member is highly important in maintaining the desired constant engagement of the window member with the vertical edge of the window opening. Thus, the arm 9 acts as a fulcrum when the inclined edge of the window mem- 130

ber is disengaged from its slideway, while the springs 18 transmit through the arm 15 an upward pressure upon the window member tending to swing the latter on said fulcrum 5 into engagement with the vertical edge of the window opening. Thus, there is maintained a constant engagement of the vertical edge of the window member with the corresponding edge of the window opening, so as to afford a 10 maximum support to the upper portion of the window member when its inclined portion is free. In order that the arms 9 and 15 may cross each other without interference, said arms are arranged to respectively occupy planes at opposite sides of the path of travel of the glass 5.

What we claim as our invention is:

1. In a window control mechanism, the combination with a member having a window 20 opening provided with opposed vertical and inclined edges, a vertical slideable closure for said opening, said closure conforming in shape with the window opening and being free from engagement with the inclined edge 25 thereof, except in its substantially closed position, means engaging the lower portion of said closure and providing a fulcrum therefor when the inclined edge of the closure is disengaged from the corresponding edge of 30 the opening and means engaging said closure adjacent the inclined edge thereof and laterally outward from said fulcrum tending to rock said closure on said fulcrum and force the same at all times against the vertical edge 35 of said opening.

2. In a window control mechanism, the combination with a member having a window opening provided with opposed vertical and inclined edges, a vertical slideable closure for 40 said opening, said closure conforming in shape with the window opening and being free from engagement with the inclined edge thereof, except in its substantially closed position, means engaging the lower portion 45 of said closure and providing a fulcrum therefor when the inclined edge of the closure is disengaged from the corresponding edge of the opening and means engaging said closure adjacent the inclined edge thereof and 50 laterally outward from said fulcrum tending to rock said closure on said fulcrum and force the same at all times against the vertical edge of said opening, said last mentioned means also functioning as a counter- 55 balance for the closure.

3. In a window control mechanism, the combination with a member having a window opening provided with opposed vertical and inclined edges, a vertically slideable closure 60 for said opening, said closure conforming in shape to the window opening and being free from engagement with the inclined edge thereof except in its substantially closed position, operating means for the closure including a member engaging the lower portion 65

thereof and providing a fulcrum for the closure when the inclined edge thereof is disengaged from the corresponding edge of said opening, and means engaging said closure adjacent the inclined edge of the 70 same and laterally outward from said fulcrum tending to rock said closure thereon and force the same at all times against the vertical edge of said opening.

4. In a window control mechanism, the combination with a member having a window opening provided with opposed vertical and inclined edges, a vertically slideable closure for said opening, said closure conforming in shape to the window opening and being free 80 from engagement with the inclined edge thereof except in its substantially closed position, operating means for the closure including a member engaging the lower portion thereof and providing a fulcrum for the 85 closure when the inclined edge thereof is disengaged from the corresponding edge of said opening, and means engaging said closure adjacent the inclined edge of the same and laterally outward from said fulcrum 90 tending to rock said closure thereon and force the same at all times against the vertical edge of said opening, said means also functioning as a counterbalance for said closure. 95

In testimony whereof we affix our signatures.

JOHN D. LAWRENCE.
